FRAME FOR MIRRORS, PICTURES, AND THE LIKE

Filed March 6, 1930

Inventor,
John Joseph Sheehan.

By *Samuel W. Balch*
Attorney.

UNITED STATES PATENT OFFICE

JOHN JOSEPH SHEEHAN, OF NEW YORK, N. Y.

FRAME FOR MIRRORS, PICTURES, AND THE LIKE

Application filed March 6, 1930. Serial No. 433,564.

The object of this invention is to provide a frame which can be readily opened for the insertion or replacement of the elements which it is to hold and display, and in which, when closed, the means for fastening are in part utilized for the support of the frame from a base. A further object is to provide a frame which is double facing and which may be set at any desired angle with respect to the base.

In the accompanying sheet of drawings which forms a part of this description,

Figure 1 is an elevation of a frame and base which embodies this invention,

Fig. 2 is a vertical section through the frame and base on the line II—II of Fig. 1,

Fig. 3 is a perspective view of the frame and base,

Fig. 4 is a perspective view of the meeting ends of the upper horizontal run of the frame, and

Fig. 5 is a perspective view of the meeting ends of the lower horizontal run of the frame.

The frame consists of two channels 10, 11, each of which includes in one piece, part of the upper horizontal run, one of the vertical runs, and part of the lower horizontal run. As shown, the runs meet at right angles, but it is not essential that they should make sharp corners. The two parts of the upper run are connected by a catch consisting of a leaf 12 with a pin 13. The leaf is attached to one part of the run within the channel and projects into the channel of the other part of the run and the pin engages a hole in this part of the run. The leaf is preferably sufficiently elastic so that disengagement may be effected by pushing down on the pin and thereby flexing the leaf, or if the leaf is too stiff to flex the disengagement may be effected by relative displacement vertically of the two parts of the horizontal run. But disengagement in this way or separation of the parts of the upper horizontal run cannot be effected until the parts of the lower horizontal run are also disconnected.

The two parts of the lower horizontal run, each have a downwardly projecting hinge eye so located that the two can be brought together and inserted in a fork 15 and secured

in the fork by a screw hinge-pin 16. The fork has a downwardly projecting swivel pin 17 which sets in a base 18. In the base is a snap button 19 which engages the end of the swivel pin.

In order that the joints in the frame may be concealed as viewed from either face, strap pieces 20, 20 are added to the sides over the joints. Each strap piece is made a permanent part of one of the parts of the frame, as by soldering, but not of the other part.

As illustrated, the frame is shown as containing on one side a plane mirror 21, or this may denote a picture or other matter to be displayed and on the other side a concave mirror 22. As the concave mirror is circular and the frame is rectangular the intervening space is occupied by a mat 23. However, it is not limited to this use of holding mirrors.

To separate the parts of the frame for insertion or replacement, the screw hinge pin is first taken out and the hinge eyes removed from the fork. This releases the two parts of the lower horizontal run from each other. The two parts of the upper horizontal run can then readily be disconnected, either by pushing down on the engaging pin or by relative vertical displacement of the two parts of the frame sufficiently to disengage the pin from the hole. The parts are then separated horizontally.

I claim,

1. A frame consisting of two channels each of which includes in one piece part of the upper horizontal run one of the vertical runs and part of the lower horizontal run, a catch for joining the channels in the upper horizontal run, a downwardly projecting hinge eye from each channel in the lower horizontal run, a base, a fork carried by the base, and means for joining the hinge eyes to the fork to secure them together and hold the picture frame at any desired angle with respect to the base.

2. A double-facing frame consisting of two channels each of which includes in one piece part of the upper horizontal run one of the vertical runs and part of the lower horizontal run, a catch for joining the channels in
